(57) **CLAIM**

The design for a movable container, as shown and described.

DESCRIPTION

FIG. 1 is a perspective view of a movable container showing our new design;

FIG. 2 is a side view thereof;

FIG. 3 is a top view thereof;

FIG. 4 is an end view thereof viewed from the left side of FIG. 2;

FIG. 5 is a bottom view thereof;

FIG. 6 is a bottom view thereof showing an alternative embodiment of our new design;

FIG. 7 is a side view of the alternative embodiment; and, FIG. 8 is the opposite side view of the alternative embodiment.

The perspective, top and end views of the alternative embodiment of FIG. 6 are identical to FIGS. 1, 3 and 4.

1 Claim, 4 Drawing Sheets

FIG. 1

FIG. 2

FIG. 3

FIG. 4

FIG. 5
